RAILROAD JOURNAL BOX

Richard J. Brittain, Jr., Berkeley Heights, N. J.,
assignor to General Motors Corporation, De-
troit, Mich., a corporation of Delaware

Application November 15, 1949, Serial No. 127,495

12 Claims. (Cl. 308—41)

1

This invention relates to railroad journal boxes and comprises all of the features of novelty herein disclosed. An object of the invention is to provide an improved thrust construction for journal boxes, especially a cushioned thrust construction which can be conveniently assembled and adjusted with a removable end cap. To this end and also to improve generally upon devices of this character, the invention consists in the various matters hereinafter described and claimed. In the drawings,

Fig. 1 is a vertical longitudinal section at the outer or front half of the box.

Fig. 2 is a central horizontal section of one half of Fig. 1.

Fig. 3 is an enlarged cross section of a bumper or cushion.

Fig. 4 is in part an end view of Fig. 1 with other parts in vertical cross section.

Fig. 5 is an inside end view of the end cap shown in Fig. 6.

Fig. 6 is a vertical central section of Fig. 5.

Fig. 7 is a cross section on line 7—7 of Fig. 5.

Fig. 8 is one half a top view and one half a horizontal section on the line 8—8 of Fig. 9, the figures being enlarged views of the thrust block.

Fig. 9 is an end view of Fig. 8.

Fig. 10 is a detail section on line 10—10 of Fig. 9.

Fig. 11 is a central vertical section of Figs. 8 and 9.

Fig. 12 is a bottom view of a portion of Fig. 11.

Fig. 13 is an end view of Fig. 8 showing the end opposite to Fig. 9.

Fig. 14 is a view looking radially at Fig. 13.

Fig. 15 is a vertical longitudinal section of a modification.

Only the outer or front portion of the journal box 2 is shown in the drawings since the inner or rear portion is desirably similar to or the same as the Brittain Patent 2,245,323. Roller bearings 4 having cages are interposed between a bearing sleeve 6 in the box and a bearing sleeve 8 on the axle 10. An oil collecting ring 12 surrounding the end of the axle and the sleeve 6 gathers oil from the bearings and delivers it to the thrust block 14 which is partially housed in a recessed end cap 16 bolted to the box. The end of the box has an inwardly projecting flange 18 whose outer face is flat and engaged by one of a series of spacing washers or shims 20 interposed between the flat face and an outwardly extending flange 22 on the end cap. Also engaging the spacing shims at three or more locations inside of the flange 22 is a series of flatfaced lugs 24 projecting from the

2

thrust block into oversize recesses 26 in the end cap. The side faces of the lugs are flush with the face of the end cap flange when the end cap is bolted on.

5 The end cap has a circular recess 28 deeper than the recesses 26 and open towards the box. It is formed in part by a tapering conical wall 30 which projects inwardly and decreases in diameter towards the box. The end of the wall 30 is joined to a flat wall 32. The wall 30 forms a dividing wall between the recess 28 and a smaller recess in the end cap and open away from the end of the box for cooling purposes. The thrust block has a flat facing 34 of bronze cast upon it and intermittently engaged by the axle when the latter shifts axially. This face has a groove 35 eccentric to the thrust block and supplied with oil from a cavity 36 below the drain lip of the oil collecting ring 12. The "lateral" or space between the axle and the thrust block can be varied as desired by making the shims 20 of varying thicknesses, or by varying the number used. A witness groove 37 indicates a certain amount of wear of the thrust block. The thrust block has an internal conical wall 38 which extends into the recess 28 of the end cap where it terminates in a narrow annular flat face 40 adapted to abut against the bottom of the recess 28 if the axle engages the thrust block with sufficient force to overcome the resistance of a resilient bumper or cushion 42.

The bumper or cushion as shown in Fig. 2, comprises a conical ring of synthetic rubber or the like between an outer conical metal ring 44 and an inner conical metal ring 46. When the end cap is bolted on, the conical faces apply an initial load to the bumper thereby causing one end 48 of the bumper to engage the thrust block in the region where a flat face or wall 49 having an opening 50 joins the conical wall 38, the other end 51 of the bumper engaging the end cap where a tapering projection formed by the conical wall 30 joins a flat face on the end cap. The conical rings 44 and 46 are bonded to the bumper along its greater portion but one end of each plate extends beyond the bumper, and one end of each plate terminates short of the end of the bumper. The bottom of the thrust block has a shallow drain groove 52 from which a deeper recess 54 extends upwardly; extending into this recess is a screw 56 carried by one of a series of arcuate lateral projections 58 on the end cap. The screw holds the end cap, bumper and thrust block together as a unit-handling device. The bumper is under an initial load when the end cap is bolted

to the box, the three lugs 24 bearing against the washers 20 which engage the box flange 18 and the end cap flange 22. When the thrust block has received an undesirable amount of wear, a selected one of the shims 20 can be removed to restore the thrust surface to its initial distance from the axle and the preload on the cushion remains the same. The thrust block is supported by the cushion with clearance in the box opening and hence can align itself with the axle under a heavy thrust load.

In Fig. 15, the same thrust block 14 and bumper 42 are used with an adapter 16A for supporting a generator driven by the axle. The adapter is bolted to the box in the same manner as the end cap 16 and has some of the corresponding parts indicated by numerals 22A, 26A and 30A. The conical wall 30A however terminates in an opening 60 concentric with the opening 50 in the thrust block so that a drive shaft can pass through. The adapter has a flanged extension 62 to which a cap 64 is bolted, the cap having an opening closed by a cover 66.

I claim:

1. In a journal box having an axle journalled for rotation and axial shifting therein, an end cap removably secured to the box, a thrust block spaced from the end of the axle, the end cap having an internal recess open towards the box and an external and smaller recess open away from the box, said recesses having a common dividing wall projecting inwardly towards the axle from the end cap, the thrust block having a portion extending into the larger recess, and internally recessed to receive the dividing wall, a cushion between the thrust block and the end cap, and mechanism demountably securing the thrust block and the cushion in unit-handling relation with the end cap.

2. In a journal box having an axle journalled for rotation and axial shifting therein, a recessed end cap removably secured to and closing an end of the box, a thrust block spaced from the end of the axle, the thrust block having a portion extending into the recess in the end cap and provided with a tapering internal recess formed by a conical wall, the end cap having a tapering projection extending into the tapering recess within the thrust block and formed by a conical wall, an end cap wall closing the inner end of the tapering projection within the thrust block recess, and a hollow conical cushion between the conical walls.

3. In a journal box having an axle journalled for rotation and axial shifting therein, a recessed end cap removably secured to and closing an end of the box, a thrust block spaced from the end of the axle, the thrust block having a portion extending into the recess in the end cap and provided with a tapering internal recess formed by a conical wall, the end cap having a tapering projection extending into the tapering recess and formed by a conical wall, a hollow conical cushion between the conical walls, and a member on the end cap demountably holding the thrust block and the cushion to the end cap as a unit therewith.

4. In a journal box having an axle journalled for rotation and axial shifting therein, a recessed end cap removably secured to the box, a thrust block spaced from the end of the axle and contained partly within the box and partly within the recess of the end cap, the portion within the end cap having a conical wall forming an internal recess, the end cap having a conical pro-

jection extending into the recess, a conical cushion interposed between the conical wall and the conical projection, and mechanism on the end cap securing the thrust block and cushion in unit-handling relation with the end cap.

5. In a journal box having an axle journalled for rotation and axial shifting therein, an end cap removably secured to and closing an end of the box, a thrust block spaced from the end of the axle and having a conical wall forming an internal conical recess, the end cap having a conical projection closed at its inner end and extending toward the axle and into the recess, a conical cushion interposed between the conical walls, and the cushion comprising a resilient annular member with inner and outer conical metal rings bonded to it.

6. In a journal box having an axle journalled for rotation and axial shifting therein, an end cap removably secured to and closing an end of the box, a thrust block spaced from the end of the axle and having a conical wall forming an internal conical recess, the end cap having a conical projection closed at its inner end and extending into the recess, a conical cushion interposed between the conical walls, the cushion comprising a resilient member with inner and outer conical metal rings bonded to it, and each of said rings terminating at one end short of the end of the cushion.

7. In a journal box having an axle journalled for rotation and axial shifting therein, a recessed end cap removably secured to and closing an end of the box, the end cap having a central tapering projection extending inwardly towards the box with an annular recess outside of said projection, a tapering annular cushion seated against the central projection and entering the annular recess, a thrust block having a surface spaced from the axle and an opposite tapering surface engaging the cushion, a member in said end cap securing the thrust block and said cushion in unit-handling relation with the end cap, and mechanism holding the cushion under compression in engagement with the thrust block and with the end cap.

8. In a journal box having an axle journalled for rotation and axial shifting therein, an end cap removably secured to and closing an end of the box and having a circular recess, a thrust block contained partly within the box and partly within the recess of the end cap, the end cap having an annular series of peripherally spaced projections extending axially into the box and positioned around the thrust block, peripherally spaced thrust block projections respectively located between adjacent end cap projections and engaging the box for normally locating the thrust block in spaced relation to the end of the axle, and a conical rubber-like cushion entering the recess and compressed against the thrust block and against the end cap.

9. In a journal box having an axle journalled for rotation and axial shifting therein, an end cap removably secured to the box, a thrust block spaced from the end of the axle, a cushion engaging the end cap and the thrust block, the box having an inwardly extending flange surrounding the thrust block, the end cap having an outwardly extending flange and an annular series of internal recesses, the thrust block having a series of lugs extending radially outwardly into the recesses with side lug faces flush with a face of the end cap flange, the flush faces overlapping said inwardly extending box flange, and means for se-

curing the end cap flange to the box flange to hold the cushion under compression.

10. In a journal box having an axle journalled for rotation and axial shifting therein, an end cap removably secured to and closing an end of the box, a thrust block spaced from the end of the axle, a cushion engaging the end cap and the thrust block, the box having an inwardly extending flange surrounding the thrust block, the end cap having an outwardly extending flange and an annularly disposed series of internal recesses, the thrust block having a series of peripherally spaced lugs extending into the recesses with side lug faces flush with a face of the end cap flange, the flush side lug faces overlapping the box flange, means for securing the end cap flange to the box flange to hold the cushion under compression, and a series of removable spacing washers interposed between all of the flush faces and said inwardly extending flange of the journal box.

11. In a journal box having an axle journalled for rotation and axial shifting therein, an end cap removably secured to and closing an end of the box, a thrust block spaced from the end of the axle, a cushion engaging the end cap and the thrust block, the box having an inwardly extending flange surrounding the thrust block, spacing washers engaging the flange, the end cap having an outwardly extending flange engaging the washers, and the thrust block having outwardly

extending lugs engaging the washers radially inside of the end cap flange and holding the cushion under compression.

12. In a journal box having an axle journalled for rotation and axial shifting therein, an end cap removably secured to the box and having a circular recess, an end cap projection axially extending within the recess towards the axle, a thrust block, a flat thrust block face engageable with the end of the axle and normally spaced from the end of the axle, the thrust block being partly within the journal box and partly within the end cap recess, and a compressed cushion fitted over the axial projection within said recess and peripherally seated against the thrust block.

RICHARD J. BRITTAINE, JR.
